A. E. SCHROEDER.

GLAZIER'S TOOL.

APPLICATION FILED NOV. 15, 1916.

1,263,129.

Patented Apr. 16, 1918.

UNITED STATES PATENT OFFICE.

ADOLPH E. SCHROEDER, OF ROZEL, KANSAS.

GLAZIER'S TOOL.

1,263,129.

Specification of Letters Patent. Patented Apr. 16, 1918.

Application filed November 15, 1916. Serial No. 131,523.

To all whom it may concern:

Be it known that I, ADOLPH E. SCHROEDER, a citizen of the United States, residing at Rozel, in the county of Pawnee and State of Kansas, have invented new and useful Improvements in Glaziers' Tools, of which the following is a specification.

This invention relates to improvements in glaziers' tools and has particular application to a device for facilitating the application of a glazier's point to a window sash for retaining the glass within the window.

The chief characteristic of this invention resides in the provision of a device of the above described character which is in the form of a hammer, the head of the hammer being provided with inclined faces and shoulders, either of the shoulders being engageable with the point while the inclined faces permit the tool to be held in convenient position for striking the point to force the same into the sash.

Another characteristic of this invention is to provide a device of the above described character which is reversible to permit the tool to be used in applying the glazier's point upon any part of the window sash without the liability of injuring the glass in any manner.

Another characteristic of this invention is to provide a device of this character which contains the desirable features of simplicity, durability and efficiency and furthermore a device which may be manufactured at a nominal cost.

Other characteristics of the invention will appear as the specification is read in connection with the accompanying drawings in which:—

Figure 1 is a side elevation of the device constructed in accordance with my invention.

Fig. 2 is a top plan view.

Fig. 3 is a bottom plan view.

Fig. 4 is an elevation of one end of the head.

Fig. 5 is an elevation of the opposite end of the head showing the cutting and breaking tool.

Referring to the drawings in detail, my invention comprises a head indicated by A and a handle B, the head is provided at its medial portion with a socket which receives one end of the handle B, any suitable means is employed for securely retaining the handle within the socket. The head is

of elongated formation and substantially rectangular in cross section, the material of which the head is constructed being of any suitable metal to obtain the result for which it is intended. One end of the head is formed with means for driving the glazier point within the window sash the said means comprising the inclined side walls 1, the said walls diverging from the inner edge to the outer edge of the head on a line diagonal with respect to the said walls of the head as is clearly illustrated in the drawings.

It will be evident that by providing the head at one end with inclined side walls, there is produced the triangular end 2. The triangular end 2 is provided with a reduced end portion 3, the side walls of the reduced portion being inclined transversely as at 4, the said reduced portion providing shoulders 5. The opposite ends of the head A or that portion which is upon the opposite side of the handle B is tapered from the handle to the free end thereof and has its outer ends in this instance provided with the glass cutting means 6 which is mounted in one of a plurality of inwardly extending recesses some of which constitute the breaking means 7.

In operation the glazier points are applied to the window sash in the usual manner so as to lie upon the pane of glass, then the tool is placed upon the pane of glass in such a manner as to cause one of the inclined sides 1 to engage the surface of the glass, the handle B being disposed at an angle to the glass to permit the proper manipulation of the tool in driving the glazier's point into the window sash. It will be evident that when the tool is in the position above stated, one of the shoulders 5 may be engaged with the edge of the glazier's point and that upon moving the tool the point will be driven into the window sash to securely retain the pane within the sash as will be understood. In providing the opposite side of the head A with the inclined side walls 1, the tool may be reversed so as to present the opposite inclined side to the surface of the glass whereupon it will be seen that this tool may be used for the driving of points upon either side of the window sash. By tapering the opposite end of the head A as has been described, this portion of the head is prevented from contacting with the

surface of the glass when using the tool for driving the glazier's point within the window sash, whereby it will be seen that the liability of the head contacting and breaking the glass during the driving operation will be eliminated.

The cutting and breaking means for the glass which is formed on one end of the head A as has been described is adapted to 10 be used in the usual manner and it is therefore thought that the detailed description of the manner of using the same is unnecessary.

It is thought from the foregoing that the 15 construction and operation of this device will be apparent to those skilled in the art and that minor changes in size, shape and proportion and minor details of construction may be made without departing from the 20 spirit and scope of the appended claim.

Copies of this patent may be obtained for five cents each, by addressing the "Commissioner of Patents, Washington, D. C."

What I claim is:—

As a new article of manufacture, a glazier's hammer head having a central portion of rectangular shape in cross section and opposite side walls converging toward each 25 other from said central portion toward one end of the head, the mentioned end of the head having a plurality of notches therein, a right angular triangular shaped beveled face on each of said side walls upon the 30 opposite side of said central portion providing the head with a striking end the opposite side edges of which converge from the back to the front of the head, and a reduced extension on the striking end of said 35 head corresponding in shape with the striking end of the head.

In testimony whereof I affix my signature.

ADOLPH E. SCHROEDER.
